UNITED STATES PATENT OFFICE.

LESTER R. WELLMAN, OF CHICAGO, ILLINOIS, ASSIGNOR TO FRIEDELEY-VOSHARDT CO., OF CHICAGO, ILLINOIS, A CORPORATION OF ILLINOIS.

DESIGN FOR AN ELECTRIC LAMP.

52,259.

Specification for Design.

Patented Aug. 6, 1918.

Application filed March 11, 1918. Serial No. 221,855. Term of patent 7 years.

To all whom it may concern:

Be it known that I, LESTER R. WELLMAN, a citizen of the United States, residing at Chicago, in the county of Cook and State of Illinois, have invented a new, original, and ornamental Design for an Electric Lamp, of which the following is the specification, reference being had to the accompanying drawing, forming part thereof.

The figure is a side elevation of an electric lamp, showing my new design.

I claim:

The ornamental design for an electric lamp substantially as shown.

LESTER R. WELLMAN.
